TELEVISION PICKUP TUBE

Alda V. Bedford, Collingswood, N. J., assignor to
Radio Corporation of America, a corporation
of Delaware

Application March 19, 1941, Serial No. 384,122

4 Claims. (Cl. 315—11)

My invention relates to cathode ray pickup tubes for picture transmission and, particularly, to pickup tubes of the type employing a low velocity scanning beam.

Pickup tubes of this type include a mosaic screen similar to that found in high velocity beam tubes, such as the Iconoscope. They also include means for producing a scanning beam in which the velocity of the electrons is so low at the mosaic screen that they do not release many secondary electrons upon striking it. Proper operation of a low velocity beam tube requires that the ratio of secondary electrons be less than unity. If, as the electron beam scans an area or spot on the mosaic, this ratio exceeds unity, the picture image for this area is not converted to a corresponding picture signal and this portion of the reproduced picture is "washed out." This is referred to as the tube "going positive" and may occur when an area on the mosaic is illuminated too strongly.

An object of the present invention is to provide an improved pickup tube of the low velocity beam type which has less tendency to "go positive" than other tubes of this type.

Stated more broadly, an object of the invention is to provide an improved means for and method of converting a light image into corresponding electrical signals.

In a preferred embodiment of the invention, the scanning beam is given such shape in cross section that the shape of the scanning spot on the mosaic screen is trapezoidal, or approximately so, with the long dimension of the spot in the direction of line scanning and with the front edge of the spot wider than the back edge. When the mosaic screen is scanned by such a spot, the picture detail over that area of the picture which is moderately illuminated is determined by the front edge of the scanning spot, since the front edge contains enough electrons to bring the mosaic elements back to their initial potential corresponding to "black" or no picture. However, the spot contains enough electrons behind the front edge to bring any brightly lighted mosaic areas, also, back to their initial or "no picture" potential, whereby these areas will not become so increasingly positive that they attract the beam electrons with sufficient velocity to make the ratio of secondary electrons to primary electrons exceed unity.

The invention will be better understood from the following description taken in connection with the accompanying drawing, in which

Figure 1 is a side view of a cathode ray pickup tube of the low velocity scanning beam type embodying my invention;

Figure 2 is an end view on an enlarged scale

of an electron gun electrode used in the tube of Figure 1;

Figure 3 is a view on a greatly enlarged scale illustrating the scanning action in tube of Figure 1; and

Figures 4 and 5 are views showing variations in the shape of the scanning spot that may be used.

Referring to Figure 1, there is shown a pickup tube 1 of the low velocity beam type described in United States Patent No. 2,213,175, issued August 27, 1940, to Iams and Rose. The particular tube illustrated is the same as described in this patent except that it is designed to have a trapezoidal scanning spot. A spot of this shape may be obtained by making the aperture in one of the gun electrodes trapezoidal in shape, as shown in the enlarged view of Figure 2.

The pickup tube 1 comprises a highly evacuated envelope having therein an electron gun which consists of an indirectly heated cathode 2, a control electrode 3, and accelerating electrodes 4 and 6. Suitable biasing and accelerating voltages are provided by the batteries 7 and 8, negative bias being applied to the control electrode 3 through a grid leak resistor 10.

By means of a focusing coil 9, the electron beam, leaving the electron gun is focused to a small spot on a mosaic screen 11. The screen 11 is of the well-known type commonly employed in Iconoscopes with the exception that it is made translucent whereby the image of an object 12 to be transmitted may be projected on the photo-electric elements of the screen from the back side 35 by means of a suitable optical system (not shown).

The electron beam is caused to scan the screen 11 by means of deflecting plates 14 and deflecting coils 16, the plates 14 preferably being curved as 40 described in the above-mentioned Iams and Rose patent for the purpose of eliminating distortion in scanning.

An electrode 17 having a slot 18 therein is provided for electrostatic shielding purposes. A centrally apertured electron collecting electrode 19 is provided to which the electrons of the beam not reaching the mosaic screen 11 are directed and by which they are collected.

As explained in the Iams and Rose patent, the electrons of the electron beam are directed upon the mosaic screen 11 with a very low velocity, that is, a velocity approaching zero velocity at the point of impact therewith. The importance 55 of this feature is that the electrons of the beam approach the mosaic of the point of impact with a velocity such that the ratio of secondary electrons to primary electrons is less than unity.

In operation, elemental areas of the mosaic 80 electrode 11 acquire electrostatic potentials pro-

portional to the intensity of light incident thereon. Particles or elements of the mosaic which are more highly illuminated acquire the most positive electrostatic charge with respect to the un-illuminated particles. The positive charges representing an electrostatic image of a picture to be transmitted are neutralized by the scanning beam electrons. When the electrons of the scanning beam are directed toward those elements of the mosaic which are negative with respect to the cathode, they cannot reach those elements because of their low velocity. These electrons, since they are prevented from impinging upon the mosaic, are returned to an electron collecting electrode adjacent the electron gun. The scanning means which cause the electron beam to scan over the mosaic electrode or target are so chosen as to prevent those electrons of the beam which do not reach the target from returning to the electron gun but rather causes them to be redirected along paths other than those followed by those electrons in traversing the distance between the electron gun and the target.

A tube of this type has a linear characteristic between light input and signal output. It is so adjusted that, when the mosaic screen 11 is dark, all of the electrons of the electron beam are repelled and returned to the collector electrode 19. Any light on the screen 11 causes some of the electrons of the beam to reach the screen for neutralizing the positive charges which the light has caused the photoelectric capacity element to assume. This neutralizing current is the picture current. Preferably, it is taken off the back or signal plate of the screen 11 and supplied to a picture amplifier (not shown). In accordance with one specific embodiment of my invention, the electron gun of the tube 1 is so designed as to make the scanning beam trapezoidal in cross-section at the mosaic screen 11. This may be accomplished by providing the accelerating electrode 4 with an aperture 4a which is trapezoidal in shape, as shown in the enlarged view of Fig. 2.

It will be understood that I have described one specific tube and one particular method of obtaining the desired spot shape merely by way of example and that my invention is not limited to this particular tube or method of shaping the spot.

In Fig. 3, I have indicated the scanning path or line traced on the mosaic screen 11 by successive scannings in the tube of Figure 1. In Figure 3, the scanning line pitch is indicated at p. Three scanning lines are shown which have been traced by a scanning beam having the trapezoidal spot shape illustrated.

Preferably, there is a slight amount of overlap of the scanning lines such as that represented by d.

One of the main characteristics of the scanning spot is that it is long (in the direction of line scanning) compared with its width. As illustrated by way of example, the length of the spot is twice the scanning line pitch. Thus, the spot contains enough electrons behind the front edge to bring the mosaic elements under a brightly illuminated area back to their original potential in the event the front edge does not contain sufficient electrons to accomplish this. The result is that, while the picture detail for such brightly illuminated areas may be reduced somewhat, as compared with the use of a shorter spot, it is

much better to have such reduction in detail for these areas than to have these areas "going positive" every now and then, whereby all detail for them is lost.

5 It may be found in some cases that a rectangular spot which is long in the direction of scanning, as shown in Figure 4, may be utilized rather than a trapezoidal spot. The reason the trapezoidal spot is preferred is that it is difficult to 10 shape and deflect an electron beam with such exactness that the front edge of a rectangular spot would always scan ahead of the rest of the spot.

As a practical matter, the "trapezoidal" shape 15 spot would probably be rounded off at the corners and have an appearance at the screen 11 similar to that shown in Figure 5. All of the spot shapes illustrated, however, have in common the characteristic of providing a large number of beam 20 electrons for a given mosaic element after the front edge of the spot has scanned this element. Thus, the tendency for the element to "go positive" is reduced.

I claim as my invention:

25 1. The method of reducing the tendency of a low velocity beam pickup tube to go positive which comprises scanning the mosaic screen of said tube with an electron beam of such cross section that the scanning spot on the mosaic is at least approximately trapezoidal in shape with the greatest dimension in the direction of line scanning and with the maximum width at the front end of the spot.

2. A cathode ray pickup tube comprising a 30 mosaic screen having a multitude of elements each capable of storing an electric charge corresponding to the light intensity of a picture element, and means for producing an electron scanning beam having a certain shape in cross section at said screen and for directing it against said elements with such low velocity that the ratio of secondary electrons to primary electrons is normally less than unity, said shape being such that the length of the scanning spot on the screen 35 in the direction of line scanning is greater than its maximum width.

3. In a picture transmitting system, a cathode 40 ray pickup tube of the type having a mosaic of electron emissive capacity elements and having means for producing an electron beam and directing it against said mosaic to form a scanning spot thereon having a certain shape, the electrons in said beam approaching zero velocity at the point of impact on said mosaic and having substantially zero velocity in the region of said mosaic 45 when it is dark, said spot having greater length in the direction of line scanning than width and its width near the front edge being greater than the width near the back edge.

4. In a picture transmitting system, a cathode 50 ray pickup tube of the type having a mosaic of electron emissive capacity elements and having means for producing an electron beam and directing it against said mosaic to form a scanning spot thereon having a certain shape, the electrons in said beam approaching zero velocity at the point of impact on said mosaic and having substantially zero velocity in the region of said mosaic 55 when it is dark, said spot being at least approximately trapezoidal in shape with the front edge wider than the back edge.

ALDA V. BEDFORD.
